(57) **CLAIM**

The ornamental design for a pair of vehicle rear fenders, as shown and described.

DESCRIPTION

FIG. 1 is a right upper perspective view of a pair of vehicle rear fenders showing my new design;

FIG. 2 is a right side elevational view thereof;

FIG. 3 is a rear side elevational view thereof;

FIG. 4 is a front side elevational view thereof;

FIG. 5 top plan view thereof; and,

FIG. 6 is a bottom plan view thereof.

The dash-dash even broken lines illustrate and surround portions of the pair of vehicle rear fenders that form no part of the claimed design.

The “long dash-short dash-short dash” broken lines shown in the drawings illustrate vehicle environmental subject matter which forms no part of the claimed design.

The other of the pair of vehicle rear fenders, having a mirror image, is not separately illustrated in the drawing views.
